UNITED STATES PATENT OFFICE.

JOHN O. HUNT, OF BROOKLYN, NEW YORK, ASSIGNOR TO INDEPENDENT PAPER MILLS INC., OF BROOKLYN, NEW YORK, A CORPORATION OF NEW YORK.

PAPER-FOLDING MACHINE.

Application filed December 24, 1923. Serial No. 682,450.

My present invention relates to a paper folding machine and more particularly to that type of machine in which a moving web of paper as supplied from a reel or 5 similar source is folded longitudinally into a predetermined number of pre-arranged sections. In machines of this type, as heretofore constructed, difficulties have been experienced with properly feeding the paper 10 to the apparatus resulting in unnecessary losses of time; and also in machines of the type to which my invention relates there has been a common tendency to exert an uneven tension on one side or the other of the paper 15 web as folded making it difficult to properly deliver and stack the folded web after the same has been cut and ejected from the apparatus. The object of my present invention is to overcome these and other difficulties by the provision of a paper folding 20 machine in which the folder members are adjustable to position relatively to each other, being movable relatively to one another to feed the paper between the same 25 and being adapted to be set in place relatively to one another to effect an even distribution of the tension as applied to the different sections of the folded web as the same is moved between the folder members and 30 folded thereby. The apparatus also includes suitable devices over which the web is moved to suitably spread the same and apply a lateral tension thereto before the web enters the folding devices in order to 35 insure the proper spread of the web to prevent the same from being turned or folded otherwise than intended in passing through the folder device. The apparatus also includes suitable roller or other devices for 40 creasing the web after it has been folded and for delivering or feeding the folded web to suitable devices for severing the same transversely, preferably folding each severed section also transversely and stacking 45 the sections thus severed from the web, which latter features, however, form no part of my present invention.

The paper folder machine made in accordance with this invention will be herein- 50 after more particularly described in conjunction with the accompanying drawings, in which,—

Fig. 1 is a diagrammatic side elevation and partial cross section illustrating the ap- 55 paratus.

Fig. 2 is an end elevation and partial section on line 2—2, Fig. 1.

Fig. 3 is an enlarged plan of the folder device of the apparatus.

Fig. 4 is an enlarged front elevation of 60 the folding device.

Fig. 5 is a sectional plan on line 5—5, Fig. 4.

Fig. 6 is a sectional elevation on line 6—6, 65 Fig. 4.

Fig. 7 is an end elevation of the folder device.

Fig. 8 is a perspective view showing the manner in which a web of paper is folded by the folder device. 70

Fig. 9 is a perspective view of the block forming one part of the folder device.

Fig. 10 is a perspective view of a block forming part of another member of the folder device, and 75

Fig. 11 is a diagrammatic plan on an enlarged scale illustrating the manner in which the paper web passes from the folder device which is also shown in Fig. 3.

Referring to the drawing and more particularly at first to Figs. 1 and 2 thereof, the apparatus includes in part a reel frame comprising a base 10 upon which suitable uprights are mounted and provided with inclined faces 11 and 12 adapted to support 80 the end portions of a spindle 13 upon which a reel of paper 14 is mounted. The paper as drawn from the reel passes over or against a roller 15 with which the paper is maintained in contact by the action of gravity causing the paper reel and the spindle upon which it is mounted to pass down the inclined faces as the reel is unwound. The paper also passes over an auxiliary roller 16 before leaving the reel frame, as is clearly indicated in Fig. 1, in which figure also the paper web is designated at 17. 90

The paper web folding mechanism includes a base 18 upon which the frame 19 is supported and suitable folder devices, one 100 of which is stationary and the other adjustably movable and each of which includes a folder block and suitable folder members, as hereinafter described. The block of the stationary part of the folder device is indicated at 20 and is secured to the frame 19 by means of screws 21 or otherwise. The block of the movable part of the folder device is indicated at 22. This is connected 105 by means of screws 23 or otherwise to a suit- 110

able head 24 at one end of an arm 25 which at the other end is provided with a bearing 26 adapted to slide on a post 27 secured to and extending from the frame 19. The bearing 26 is fitted with a stop screw 28 adapted at one end to bear against the frame 19 to determine the position of the movable part of the folder device relatively to the stationary part thereof, and also with a set 10 screw 29 by means of which the stationary part of the folder device may be fixed in any adjusted position.

The block 20 forming part of the fixed or stationary member of the folder device 15 is preferably double wedged shape as indicated in Fig. 10 of the drawing and may be made of wood, metal or any other suitable material. This member consequently has four triangular faces and a corresponding 20 number of corners indicated respectively at *a*, *b*, *c*, *d*. The face 30 of this folder block is the rear face and is the face included between the corners *a*, *b*, *d*. This is the face which lies next the frame member 19. The 25 side faces of the block 20 are indicated at 31, 32 and are defined respectively between the edges *a*, *b*, *c* and *d*, *b*, *c*. These faces as clearly indicated in the drawing are inclined upwardly and their forward edges 30 are inclined upwardly and outwardly. The outer face of the block 20 is indicated at 33 and is defined by the corners *a*, *c*, *d*. This face inclines upwardly and outwardly and terminates at the point or corner *c* which is 35 in line with the corner *b* at the apex of the inner face 30. Lying between the inner face 30 of the block member 20 and the frame 19 is a back or liner 34 preferably made of sheet metal, although, as will be 40 understood, it may be formed of any suitable material. Externally of the edges of the back face 30 of the block member 20 this liner 34 is extended to form folder members 35 and 36 respectively which are 45 suitably shaped to conform to but are spaced from the oppositely disposed sides 31 and 32 of the block 20, the lower portions of these folder members being curved to gradually bring a section of paper web between 50 the same and parts of cooperating members secured to the movable part of the folder device as hereinafter more particularly described.

The block 22 forming part of the movable member of the folder device is made 55 in the form of a pyramid and consequently has four faces defined between the apex *e* and the corners of the base as indicated at *f*, *g*, *h* and *i*. The inner face of this block 60 is indicated at 37 and is defined by the corners *e*, *i* and *h* and this is the face which lies against the head 24 and is connected thereto. The outer face of this block 22 65 is indicated at 38 and is defined by the corners *e*, *f* and *g*. The side faces of this

block are indicated at 39 and 40 respectively and are defined by the corners *e*, *f*, and *i* and *e*, *g* and *h*. The outer face 38 inclines upwardly at the same angle as the outer face 33 of the block 20 and the side 70 faces 39 and 40 are inclined upwardly at the same angles as the side faces 31 and 32 of the block 20 so that when in position for use the outer face 38 of the block 22 assumes a position which is juxtaposed to 75 the face 33, while the face 39 of this movable block lies in the same plane as the face 31 of the stationary block and the side face 40 of the movable block lies in the same plane as the side face 32 of the stationary 80 block. The stationary block 22 at the opposite side faces thereof has folder members 41 and 42 suitably secured thereto. These folder members conform approximately to the outlines of the faces of the block and 85 to the corresponding faces of the fixed or stationary block with which they are parallel so that at their upper extremities these folder members are of approximately the same width as the top edge of the stationary block. Also as indicated in Figs. 4 and 5 of the drawing the folder member 42 may have associated therewith an auxiliary folder 90 43 for a purpose to be hereinafter more particularly described. 95

The apparatus also includes a set of rollers for spreading and placing a lateral tension in the parts of the web as the same is fed to the folder devices. For this purpose I may employ suitable brackets 44. 100 These brackets are connected to the end faces of a base 45 by rivets 46 or otherwise to which the movable block 22 is also connected. Associated with the brackets 44 are bracket arms 47 and 48. These brackets 105 arms 47 and 48 are connected to the base 45 and the brackets 44 in any suitable manner. Journaled between the ends of the brackets 44 is a roller 49. Journaled between one end of the bracket 45 and the end of the 110 bracket 48 is a roller 50, and journaled between the other bracket 44 and the end of the bracket arm 47 is a roller 51. The axes of the rollers 49, 50 and 51 all lie in the same horizontal plane, but the axes of the rollers 50 and 51 are offset at a predetermined angle, preferably at an angle of approximately 20° to the axis of the roller 49. Furthermore each of the rollers 50 and 51 are substantially one-half the length 115 of the roller 49 for the purpose of folding the paper in the manner as designed by the machine as illustrated and described, other arrangements of rollers being adapted for use in otherwise folding the paper. 120

The machine as herein illustrated is adapted to fold a web of paper longitudinally into three sections of substantially the same width and a fourth and fifth section of variable but lesser widths, as clearly illus- 125 130

trated in Fig. 8 of the drawing. The inner of these sections of the paper web is indicated at 52. The intermediate sections are indicated at 53 and 54 and the outer narrower sections are indicated at 55 and 56. After the paper web has been folded it is carried through rolls 57 and 58 to suitably crease the same and from these rolls 57 and 58 it passes over a drum 59 and a feed roll 60 for delivering the paper to a suitable severing mechanism and other devices which form no part of my present invention.

In the use of the apparatus, as hereinbefore described, the parts of the movably adjustable member of the folder device are shifted along the post 27 away from the fixed members of the device in order to permit the operator to readily feed the web to the folder mechanism. With the web placed over the parts of the movable member of the folder device the same is shifted to its associated position with the fixed member. In so doing as will be understood the web passes over the rollers 49, 50 and 51 and is stretched laterally thereby causing a predetermined extent of lateral tension to be exerted against the web. It will also be apparent that the folder member 41 passes within the folder member 35 and the folder member 42 passes within the folder member 36, while the folder member 36 passes within the auxiliary folder member 43, the parts being adjusted to position in such a manner as to place the desired degree of tension on the paper web while being drawn through or between these folder members, this naturally being determined upon by the nature or texture of the paper which is being folded. In this folding operation, as will be apparent, the adjacent sections 52 and 53 of the web are folded over the edge of the folder member 41, the web section 52 passing between the folder member 35 and the adjacent face of the folder member 41, while the web section 53 passes between the other face of the folder member 41 and the face 31 of the stationary block 20, while the web section 54 passes between the face 32 of the stationary block 20 and the adjacent face of the folder member 42, these intermediate web sections 52 and 54 being folded over the upper corner of the stationary block as indicated at c. The web sections 54 and 55 are folded over the edge of the folder member 42 and the web section 55 passes between the outer face of the folder member 42 and the inner face of the folder member 36. The outer sections 55 and 56 are folded over the edge of the folder member 36 and the outer web section 55 passes between the outer face of the folder member 36 and the inner face of the folder member 43.

It will be understood that the brackets and rollers 49, 50 and 51 may be adjustable relatively to the lower edges of the movable

block so as to bring the paper web as it passes over the rollers into the proper position to be fed directly between the folder members, this in turn depending upon the nature of the paper being handled by the machine. If necessary also the creaser rollers 57 and 58 may be adjustable to position in order to vary the extent of the crease as made in the folded paper.

I claim as my invention:

1. In a machine for folding a web of traveling paper into a plurality of longitudinal sections, folder members adjustable to position relatively to one another for longitudinally folding a paper web in passing between the same, and devices relatively movable with respect to one of the folder members, for stressing the web transversely thereof before it enters the said folder members the relative positions of the two folder members determining the stress imposed on the web.

2. In a machine for folding a web of traveling paper into a plurality of longitudinal sections, folder members adjustable to position relatively to one another for longitudinally folding a paper web in passing between the same, devices relatively movable with respect to one of the folder members, for stressing the web transversely thereof as it enters the folder members, the relative positions of the two folder members determining the stress imposed on the web, and means for creasing the folded web after it leaves the folder members.

3. In a machine for folding a web of traveling paper into a plurality of longitudinal sections, a stationary folder member, and a folder member shiftable to position toward and away from the stationary folder member, one of the folder members having a plurality of cooperating substantially triangular faces, each of which has an edge in common with the others for longitudinally folding the web in passing between the said folder members.

4. In a machine for folding a web of traveling paper into a plurality of longitudinal sections, a stationary folder member, a folder member shiftable to position relatively to the stationary folder member, and adapted to coat therewith for longitudinally folding a web of paper in passing between the said folder members, and devices attached to one of the folder members for stressing the web transversely thereof before it passes between the said folder members whereby the relative positions of the two folder members determines the stress imposed on the web.

5. In a machine for folding a web of traveling paper into a plurality of longitudinal sections, a stationary folder member, a folder member shiftable to position relatively to the stationary folder member,

- and adapted to coact therewith for longitudinally folding a paper web in passing between the said folder members, the movement of the shiftable folder member permitting the threading of the paper web between the folder members, devices for stressing the web transversely thereof before it passes between the stationary and shiftable folder members, and means for creasing the folded paper web after it passes from the said folder members.
6. In a machine for folding a web of traveling paper into a plurality of longitudinal sections, a stationary folder member, a folder member shiftable to position toward and away from the stationary folder member to determine the space between the said members when in operation, devices variably positionable with respect to one of the folder members, for stressing the paper web transversely thereof as it enters the said folder members, the movement of the shiftable folder member permitting the threading of the web between the folder members, and the relative positions of the two folder members determining the transverse stress imposed on the web, and means for creasing the folded web after it passes from the said folder members.
7. In a machine for folding a web of traveling paper into a plurality of longitudinal sections, a stationary folder member, a folder member shiftable to position relatively to the stationary folder member, one of the folder members having three cooperating substantially triangular faces, the vertex of the central face being at one end of a base common to the other two faces and means for adjusting the extent to which the last aforesaid folder member is shiftable toward the stationary folder member to determine the space between the said folder members when in operation, the said folder members being adapted to cooperate with one another to produce a plurality of longitudinal folds in a paper web while the same is passing between them.
8. In a machine for folding a web of traveling paper into a plurality of longitudinal sections, a stationary folder member, a variably positionable folder member, one of the folder members being shaped like a double wedge, with the thin edges at opposite ends thereof, and substantially at right angles to each other, a frame upon which the variably positionable folder member is mounted, devices upon which the said frame and its folder member are shiftable to position toward and away from the said stationary folder member, the movement of the movable folder member permitting the threading of the web between the two folder members, and devices for determining the relative operating positions of the said folder members, which are adapted to cooperate with

one another in producing a plurality of longitudinal folds in a paper web while passing between them.

9. In a machine for folding a web of traveling paper into a plurality of longitudinal sections, a stationary folder member, a variably positionable folder member, a frame upon which the variably positionable folder member is mounted, devices upon which the frame and its folder member are shiftable toward and away from the said stationary folder member, one of the folder members having a plurality of substantially triangular faces, the movement of the movable folder member away from the stationary folder member permitting the threading of the web between the two folder members, means for determining the relative operating positions of the said folder members which are adapted to cooperate with one another in producing a plurality of longitudinal folds in a paper web while passing between the same, and means for securing the said frame and its movable folder member in an operative position relatively to the said stationary folder member.

10. In a machine for folding a web of traveling paper into a plurality of longitudinal sections, a stationary folder member, a variably positionable folder member, a frame upon which the movable folder member is mounted, devices upon which the frame and its folder member are shiftable toward and away from the stationary folder member, means for determining the relative operating positions of the said folder members, the folder members being adapted to cooperate with one another for producing a plurality of longitudinal folds in a paper web while passing between them, means for securing the said frame and its folder member in an operative position relatively to the stationary folder member, means for stressing the paper web transversely thereof before it enters the folder members, and means for creasing the web at the folds.

11. In a machine for folding a web of traveling paper into a plurality of longitudinal sections, a stationary folder member, a variably positionable folder member, a frame upon which the movable folder member is mounted, devices upon which the frame and its folder member are shiftable toward and away from the stationary folder member, means for determining the relative operating positions of the said folder members, the said folder members being adapted to cooperate with one another for producing a plurality of longitudinal folds in a paper web while passing between them, means for securing the said frame and its folder member in an operative position relatively to the said stationary folder member, and angularly placed rollers over which the paper web travels, and by which the web is

stressed transversely before the same enters the said folder members.

12. In a machine for folding a web of traveling paper into a plurality of longitudinal sections, a stationary folder member comprising a block having a plurality of substantially triangular faces, folder devices associated therewith, and a folder member shiftable to position relatively to the stationary folder member, and adapted to coact therewith to produce a plurality of longitudinal folds in a paper web while passing between the said folder members.

13. In a machine for folding a web of traveling paper into a plurality of longitudinal sections, a stationary folder member comprising a block having a plurality of substantially flat triangular faces, and folder devices associated therewith, and a folder member shiftable to position relatively to the said stationary folder member and comprising a block and folder devices associated therewith, the said block and folder devices associated with the said folder member being adapted to cooperate with the said block and folder devices of the stationary folder member for producing a plurality of longitudinal folds in a paper web while passing between the said folder members.

14. In a machine for folding a web of traveling paper into a plurality of longitudinal sections, a stationary folder member comprising a block having some of its faces substantially triangular and folder devices associated therewith, a folder member comprising a block having some of its faces substantially triangular and folder devices associated therewith, the said block and folder devices associated with the said folder member being adapted to cooperate with the said block and folder devices of the stationary folder member for producing a plurality of longitudinal folds in a paper web while passing between the said folder members, and means for adjusting the said folder member to position, and securing the same in place relatively to the said stationary folder member.

15. In a machine for folding a web of traveling paper into a plurality of longitudinal sections, a stationary folder member comprising a double wedge shaped block having an outer downwardly inclined face and oppositely disposed upwardly inclined faces, and folder plates overlying the said oppositely disposed side faces, and a folder member associated with the said stationary folder member and adapted to cooperate therewith for producing a plurality of longitudinal folds in a web of paper while passing between the folder members.

16. In a machine for folding a web of traveling paper into a plurality of longitudinal sections, a stationary folder member comprising a double wedge shaped block

having an outer downwardly inclined face and oppositely disposed upwardly inclined faces and folder plates overlying the said oppositely disposed side faces, a folder member comprising a block of pyramidal form having an outer upwardly inclined face adapted to cooperate with the downwardly inclined outer face of the aforesaid block and upwardly inclined oppositely disposed side faces, and folder plates associated with the oppositely disposed side faces of the pyramidal block and adapted when the movable folder member is adjusted to position to lie within the folder plates associated with the double wedge shaped block whereby the folder members and the parts thereof cooperate to effect a plurality of longitudinal folds in a paper web while passing between the same.

17. In a machine for folding a web of traveling paper into a plurality of longitudinal sections, a stationary folder member comprising a double wedge shaped block having an outer downwardly inclined face and oppositely disposed upwardly inclined faces and folder plates overlying the said oppositely disposed side faces, a folder member comprising a block of pyramidal form having an outer upwardly inclined face adapted to cooperate with the downwardly inclined outer face of the aforesaid block and upwardly inclined oppositely disposed side faces, and folder plates associated with the oppositely disposed side faces of the pyramidal block and an auxiliary folder plate associated with one of the last aforesaid folder plates, the said outer faces of the said blocks and the folder plates associated therewith being adapted to cooperate for producing a plurality of folds in a web of paper while the same is passing between the said folder members.

18. In a machine for folding a web of traveling paper into a plurality of longitudinal sections, a stationary folder member comprising a double wedge shaped block having an outer downwardly inclined face and oppositely disposed upwardly inclined faces and folder plates overlying the said oppositely disposed side faces, a folder member comprising a block of pyramidal form having an outer upwardly inclined face adapted to cooperate with the downwardly inclined outer face of the aforesaid block and upwardly inclined oppositely disposed side faces, folder plates associated with the oppositely disposed faces of the said pyramidal block, and an auxiliary folder plate associated with one of the last aforesaid folder plates, the folder plates associated with the pyramidal block being adapted to pass between the folder plates associated with the double wedge shaped block and the said auxiliary folder plate being adapted to receive a portion of the folder plate associated

- with the double wedge shaped block on the corresponding side of the folder members whereby the said outer inclined faces of the said blocks and the oppositely disposed inclined faces of the same, together with the said folder plates cooperate with each other for producing a plurality of folded sections in a paper web, the folded sections with the exception of one outermost section being of substantially the same width while the outermost section is folded into a plurality of sections of lesser width.
19. In a machine for folding a web of traveling paper into a plurality of longitudinal sections, the combination of means for folding the web longitudinally, along a line substantially at the center of the web, and folder members for folding the web in directions opposite to the first fold, these second foldings being along longitudinal lines between the first fold and the respective edges of the web, and means for creasing the folds.
20. In a machine for folding a web of traveling paper into a plurality of longitudinal sections, the combination of means for folding the web longitudinally, along a line substantially at the center of the web, a cooperating folder member for folding the web reversely, in a direction opposite to the center fold, along a line parallel to the center fold and to one side of the center fold, and cooperating folder mechanism for folding the other side of the web, on the other side of the center fold, twice, along lines parallel to the other folds, the two last folds being reverse folds with respect to each other, and means for creasing the folds thus formed.
21. In a machine for folding a web of traveling paper into a plurality of longitudinal sections, the combination of a folder block in the shape of a double wedge, the thin edges of the wedge block being at opposite ends thereof and extending in directions substantially at right angles to each other, co-operating folder members for folding the web around the said block, and means for creasing the folds thus formed.
22. In a machine for folding a web of traveling paper into a plurality of longitudinal sections, the combination of a folder block in the shape of a double wedge, the thin edges of the wedge block being at opposite ends thereof and extending in directions substantially at right angles to each other, a co-operating folder member at either side of the folder block, said parts cooperating to fold the web three times, along longitudinally extending, parallel lines, each fold being in a reverse direction with respect to an adjacent fold.
23. In a machine for folding a web of traveling paper into a plurality of longitudinal sections, the combination of a folder block in the shape of a double wedge, the thin edges of the wedge block being at opposite ends thereof and extending in directions substantially at right angles to each other, a cooperating folder member at either side of the folder block, said parts cooperating to fold the web longitudinally along a line substantially at the center of the web, and also to fold the web along longitudinal lines at either side of the center fold, said last two folds being reverse folds with respect to the center fold.
24. In a machine for folding a web of traveling paper into a plurality of longitudinal sections, the combination of means comprising a folder block in the shape of a double wedge, the thin edges of the wedge block being at opposite ends thereof and extending in directions substantially at right angles to each other, for folding the web longitudinally, along a line substantially at the center of the web, a cooperating folder member for folding the web reversely, in a direction opposite to the center fold, along a line parallel to the center fold and to one side of the center fold, and cooperating folder mechanism for folding the other side of the web, on the other side of the center fold, twice, along lines parallel to the other folds, the two last folds being reverse folds with respect to each other, and means for creasing the folds thus formed.

Signed by me this 19th day of December, 1923.

JOHN O. HUNT.
